REFRIGERATOR

Walter A. Kuenzli, Evansville, Ind., assignor to
 Servel, Inc., New York, N. Y., a corporation of
 Delaware

Application November 13, 1939, Serial No. 303,995

4 Claims. (Cl. 20—35)

This invention relates to refrigerator cabinet structure, and more particularly to breaker strip structure which spans a gap between spaced apart edges of metal wall members and serves as a connecting trim.

An object of the invention is to provide an improved breaker strip structure in which a first member formed of relatively soft or resilient material is secured to a second member having a relatively hard finished surface, the members being formed to provide grooves which receive the spaced apart edges of sheet metal wall members.

Another object of the invention is to provide such a breaker strip structure which is combined with or may be used in connection with a sealing gasket.

The invention, together with the above and other objects and advantages thereof, will be better understood from the following description taken in conjunction with the accompanying drawing forming a part of this specification, and of which:

Fig. 1 is a front elevation of a refrigerator cabinet provided with breaker strip structure embodying the invention;

Fig. 2 is a fragmentary sectional view taken on line 2—2 of Fig. 1;

Fig. 3 is a fragmentary perspective view, in section, of the resilient part of the breaker strip and sealing gasket structure shown in Fig. 2;

Figs. 4 and 5 are views similar to Figs. 2 and 3 illustrating another embodiment of the invention in which the sealing gasket is separate from the breaker strip structure.

In the drawing a refrigerator cabinet 10 is provided with a door 11 affording access into a food storage compartment 12 which is maintained at a desired low temperature by a cooling element 9 of suitable refrigeration apparatus.

Referring more particularly to Figs. 2 and 3, the door 11 includes an outer wall member 13 which is formed with a marginal edge portion 13a which is bent back upon itself to provide an inner substantially flat portion or ledge 13b having an inclined flange 13c. An inner wall member 14 is provided with an inclined flange 14a which extends toward the flange 13c. The wall members 13 and 14 are maintained in spaced relation in any suitable manner well known in the art to provide a relatively wide gap between the flanges 13c and 14a and form an insulation space between the wall members to receive suitable insulation 15.

The breaker strip structure embodying the in-

vention includes a trim strip 16, which may be formed of hard rubber, a synthetic resinous product, wood or any other material having a relatively hard surface to provide a smooth finish which is easily cleaned. A backing member 17, which may be made of soft rubber or other similar resilient material, is cemented or secured in any other suitable manner to the trim strip 16. The inner edge of the backing member 17 is offset at 18 with respect to trim strip 16 to form a channel or groove which receives the flange 14a of the inner wall member 14. The outer edge of the backing member 17 is formed with a longitudinally extending groove or channel 19a which receives the flange 13c of the outer wall member 13.

A sealing gasket 20 is formed integrally with the backing member 17. The sealing gasket 20 is provided with a hollow striking bead 21 which contacts the front of the cabinet to provide a seal when the door 11 is in its closed position.

In positioning the breaker strip construction just described, the tongues or offset edge portions 18 and 19 are bent so that they can slip into the gap between the spaced flanges 13c and 14a. After the tongues 18 and 19 are slipped into the space between the wall members 13 and 14, the trim strip 16 is pressed down so that the outer edge portions thereof overlie the flanges 13c and 14a. When this is done, the tongues 18 and 19 assume the position shown in Fig. 2 whereby the breaker strip structure is firmly held in position.

By securing a backing member 17 formed of resilient material to a relatively rigid trim strip 16, the advantages of a resilient breaker strip are obtained to facilitate the insertion and removal of the breaker strip between the spaced apart edges of sheet metal wall members. At the same time a trim strip is provided which is relatively stiff and rigid. When the trim strip 16 is formed of a synthetic resinous material like that identified by the trade-mark "Bakelite," for example, the trim strip has a hard surface which is easily cleaned and also imparts a neat appearance to the refrigerator cabinet structure.

In the embodiment of Figs. 4 and 5 the sealing gasket 30 is formed as a separate member instead of integrally with the backing member 25. In Fig. 4 the trim strip 24 overlies the flanges 23a and 22c of the inner and outer wall members 23 and 22. The flange 22c is inclined with respect to an inner ledge 22b which is formed by bending the outer edge portion 22a back upon itself. The backing member 25 of resilient material is cemented to the underside

of trim strip 24 except at its outer edge portions 26 and 28. The outer edge portions 26 and 28 are offset from the trim strip 24 to form grooves or channels to receive the flanges 22c and 23a.

The separate gasket 30 is U-shaped at 31 to form a groove to receive the flange 22c, and the end 31 of the sealing gasket 30 in turn is received by the groove formed by the outer edge portion of trim strip 24 and tongue 28. As in the embodiment described above, the sealing gasket 30 is provided with a hollow striking bead 32. The trim strip 24 may be formed of hard rubber, wood, or a synthetic resinous material as in the embodiment shown in Fig. 2, and the backing member 25 may be formed of soft rubber or other suitable resilient material. The gasket 30, like the backing member 25, may be formed of rubber or other suitable resilient material.

In the embodiment of Figs. 4 and 5, the U-shaped heel 31 of the sealing gasket 30 is first positioned over flange 22c, and the breaker strip structure is then inserted into position in the manner described above in connection with the embodiment of Figs. 2 and 3.

Although several embodiments of the invention have been shown and described, it will be apparent that modifications and changes can be made without departing from the spirit and scope of the invention. For example, the trim strip and backing member may be used alone to provide a transverse connecting wall between the spaced edges of wall members. In such case both edges of the backing member are offset with respect to the edge portions of the trim strip to provide longitudinal grooves or channels at both edges of the breaker strip structure, such grooves or channels receiving the edge portions of the spaced apart wall members. It is therefore contemplated to cover such variations and modifications which fall within the true spirit and scope of the invention, as pointed out in the following claims.

What is claimed is:

1. Refrigerator cabinet structure including inner and outer wall members terminating in 45

opposed edge portions providing a longitudinally extending space therebetween, a substantially rigid longitudinal cover strip greater in width than said space and adapted to overlie the outer surface of said edge portions, and separable fastening means comprising a backing member of resilient material affixed to the underside of said strip, said backing member having a longitudinal marginal portion spaced apart from the adjacent marginal portion of said strip to form therewith a channel having a resilient inner wall adapted to separably engage the underside of one of said edge portions.

2. The structure of claim 1 wherein the opposite marginal portion of said backing member is provided with an extension projecting beyond the adjacent margin of said cover strip and over the outer surface of the other of said edge portions, the inner side of said extension being provided with a resilient lip adapted to separably engage the under surface of said other of said edge portions.

3. The structure of claim 1 wherein the opposite marginal portion of said backing member is provided with an extension projecting beyond the adjacent margin of said cover strip and over the outer surface of the other of said edge portions, the outer longitudinal margin of said extension being provided with a sealing gasket, the inner side of said extension being provided with a resilient lip adapted to separably engage the under surface of said other of said edge portions.

4. The structure of claim 1 that includes, a gasket member formed of resilient material and having its inner longitudinal margin provided with a grooved member engaging the other of said edge portions and underlying the adjacent edge of said cover strip, the opposite marginal portion of said backing strip being spaced apart from the adjacent marginal portion of said cover strip to form therewith a channel having an inner resilient wall adapted to separably engage the innermost surface of said grooved member.

WALTER A. KUENZLI.
